UNITED STATES PATENT OFFICE.

WILLIAM H. AYRES, OF BALTIMORE, MARYLAND, ASSIGNOR TO AMERICAN CAN COMPANY, OF NEW YORK, N. Y., A CORPORATION OF NEW JERSEY.

HEAD FOR TRUING DIES.

1,332,481.

Specification of Letters Patent.

Patented Mar. 2, 1920.

Application filed June 16, 1915, Serial No. 34,422. Renewed July 14, 1919. Serial No. 310,874.

To all whom it may concern:

Be it known that I, WILLIAM HOWARD AYRES, a citizen of the United States, residing in Baltimore, State of Maryland, have invented a new and useful Improvement in Heads for Truing Dies, of which the following is a specification.

My invention relates in general to the formation of dies and has more particular reference to the formation of dies adapted to cut circular blanks of metal and the like, such, for example, as dies adapted for the cutting of can heads and end closures.

The purpose of the invention is the provision of a head for truing or shaping the die after it is formed, which may be mounted in the tail stock of a lathe and through a rolling action bring the die already formed to true and accurate condition.

20 A further object of the invention is the provision of such an instrument which may be adjusted to dies of various sizes without requiring a nicety of handling so that it may be utilized by any mechanic familiar 25 with the making of dies.

A further object of the invention is the provision of such a device of economical manufacture, simple construction and of permanently efficient and easy operation.

30 Other objects and advantages of the invention will be apparent as it is better understood from the following description when considered in connection with the accompanying drawing illustrating a preferred 35 embodiment thereof.

Referring to the drawing,

Figure 1 is a central sectional view taken through a die truing head embodying my invention;

40 Fig. 2 is a top plan view thereof; and

Fig. 3 is a section taken substantially at right angles to the plane of section of Fig. 1.

In accordance with my invention the die truing device or head is adapted to be used 45 upon an ordinary lathe and to this end the moving parts are mounted in a frame 4 provided with a stud or post 5 adapted to be inserted within the tail stock of a lathe, the die being trued being held within 50 the revolving head, as will be later described.

The truing of the die is accomplished by a plurality of profile rollers 6, two such rollers being shown in the present instance.

55 Each of the rollers 6 is provided with a

groove 7 in which the edge 8 of the die 9 (indicated in dotted lines) is adapted to be engaged. This groove is formed by an inclined spreading surface 10, of greater inclination than the inclined surface 11 of the die, and a vertical surface 12 for engagement with the outer face 13 of the die. The bottom of the groove is cut in slightly at 14 to give the desired slight extension at the edge as is desired in die presses. These rollers are preferably constructed of swaging roller tool steel hardened and they are each mounted on a spindle or shaft 15 engaged in a slide 16. A plate 17, preferably of ball bearing steel hardened, is fitted in the face 70 of the slide and between this plate and the adjacent face of the roller ball bearings 18 are inserted in suitable race-ways. Each spindle or shaft 15 has a head 19 adapted to hold the parts in place. The spindles 75 are preferably of hardened tool steel and each is embraced by a collar 21 of hardened steel, upon which the rollers 6 bear.

The slides 16, two in the present instance, move in a suitable way or groove 22 in the frame or head 4, this way being of any appropriate form to hold the slides in place and to direct their movement accurately. The slides are positioned at an equal distance from the axis of rotation of the head 85 of the lathe or an equal distance from the central axis of the stud or post 5, and they are adapted to be adjusted with respect thereto to accommodate the device to dies of different diameters. This adjustment is 90 accomplished in the present instance by a pair of shafts 23 and 24. The shaft 23 is mounted to rotate under the action of a suitable hand-wheel 25, being held against motion by a plate 26 secured on the end of 95 the frame 4 through screws or other suitable fastening means 27. The shaft 23 is in threaded engagement externally with one of the slides 16 and is in threaded engagement internally with the shaft 24, which 100 shaft is secured at its end in the other slide 16 by a pin 28 and thereby held against rotation. Turning of the hand-wheel 25 will produce a rotation of the shaft 23 and thereby produce a like movement toward or 105 from the axis of the stud 5 of both slides 16, one slide through the direct threaded engagement with the shaft 23 and the other slide with the threaded engagement with the shaft 24. A plate 29 is secured by screws 110

or other fastening means 31 to close the end of the way or guide 22 remote from the hand-wheel.

When it is desired to true a die the device 5 need only be positioned in the tail stock of a lathe and the die to be trued centered in the head of the lathe. The device is then fed forward and rotated and moved into engagement with the grooves 7 of the rollers 6. These rollers then rotate under the influence of the die and swage and shape it 10 to desired formation.

It is thought that the invention and many 15 of its attendant advantages will be understood from the foregoing description, and it will be apparent that various changes may be made in the form, construction and arrangement of the parts without departing from the spirit and scope of the claims or 20 sacrificing any of its material advantages, the form hereinbefore described being merely a preferred embodiment thereof.

I claim:

1. A head for truing dies comprising profiled rotatable shaping elements, each element being shaped to engage interiorly and exteriorly of the die entirely to the die edge, and means for holding said shaping elements in accurate position.

2. A head for truing dies comprising a plurality of profiled shaping rolls adapted to simultaneously engage the extreme edge of the die both interiorly and exteriorly, and adjusting means for connecting said rolls for moving them simultaneously toward and from a central axis.

3. A head for truing dies comprising a grooved roller having interiorly and exteriorly acting surfaces at an angle to each other, a shaft upon which said grooved roller is mounted, and means for holding said shaft in accurate position.

4. A head for truing dies comprising a pair of grooved rollers rotatably mounted 45 in alinement and at equal distances from a central axis, each roller having interiorly and exteriorly acting surfaces at an angle to each other.

5. A head for truing dies comprising a 50 body, a plurality of slides arranged thereon, a profiled shaping roller on each slide having faces intersecting at the edge of a die for engaging such die both interiorly and exteriorly, and means for moving said slides 55 simultaneously with respect to a fixed axis

or central point and in directions parallel with the axes of said profiled rollers.

6. A head for shaping dies comprising a body, slides mounted thereon, each of said slides carrying a profiled shaping roll having faces intersecting at the edge of a die for engaging such die both interiorly and exteriorly, a threaded shaft for each slide, and means for engaging the threads on each slide to produce like movement in said slides under adjustment in directions substantially parallel with the axes of said profiled rolls.

7. A head for truing dies comprising profiled rolls rotatable through the agency of the die and each shaped to act both interiorly and exteriorly on the die, and means for securing said rolls in appropriate positions nearer to or farther from each other according to the diameter of the die.

8. A head for truing dies comprising profiled shaping rolls for operating on the edge of the die at opposite sides thereof, means for supporting the rolls in position, and a post for fitting into the tail stock of a lathe arranged between said rolls and equidistant 75 from both of said rolls.

9. A head for shaping dies comprising a supporting and guiding device having means for attachment to a rotary mechanism, slides mounted on said head and adapted to be moved simultaneously and equally toward and from each other, non-rotary and rotary screw shafts connecting said slides for causing them to move in opposite directions, and profiled rollers mounted on said slides and 85 adapted to operate upon a die.

10. A tool for shaping dies, comprising a supporting and guiding device, opposing slides mounted on said guiding device and adapted to be moved simultaneously and 95 equally toward and from each other, a screw held from rotation on one of said slides, a rotary screw having a screw thread engagement with the other slide and having a screw thread engagement with said first mentioned screw, means for turning said rotary screw, and die-shaping rollers mounted on said slides.

Signed in the presence of two subscribing witnesses.
